US00D483084S

(12) **United States Design Patent** (10) Patent No.: **US D483,084 S**
Gvoich (45) Date of Patent: ** Dec. 2, 2003

(54) **EXERCISE PLATFORM**

- (75) Inventor: **Ned Gvoich, Ontario (CA)**
(73) Assignee: **GoodTimes Entertainment LLC, New York, NY (US)**
(**) Term: **14 Years**
(21) Appl. No.: **29/176,063**
(22) Filed: **Feb. 14, 2003**
(51) LOC (7) Cl. **21-02**
(52) U.S. Cl. **D21/686; D21/671**
(58) Field of Search **D21/662, 671, D21/686, 690; D6/349; 482/51, 142, 52, 140, 79; 297/423.45, 423.46**
